Primary Examiner — T Chase Nelson

(57) **CLAIM**

The ornamental design for a shoe sole as shown and described.

DESCRIPTION

FIG. 1 is a top, rear, left perspective view of a shoe sole showing my new design;

FIG. 2 is a bottom, front, right perspective view thereof;

FIG. 3 is a top view thereof;

FIG. 4 is a bottom view thereof;

FIG. 5 is a left view thereof;

FIG. 6 is a right view thereof;

FIG. 7 is a front view thereof;

FIG. 8 is a rear view thereof; and,

FIG. 9 an enlarged view of a portion labeled as 9 on FIG. 2. The broken lines illustrate portions of the shoe sole that form no part of the claimed design.

1 Claim, 9 Drawing Sheets
